ASH TRAY

Calder B. Willingham, Sr., P.O. Box 102, Rome, Ga.

Filed Sept. 30, 1960, Ser. No. 62,322

Term of patent 14 years

(Cl. D85—2)

Fig. 1

Fig. 4

Fig. 2

Fig. 3

Fig. 1 is a perspective view of an ash tray showing my new design;

Fig. 2 is a top plan view;

Fig. 3 is a sectional view taken substantially upon a plane passing along section line 3—3 of Fig. 2 illustrating the design of the transverse support; and

Fig. 4 is a fragmentary sectional view of the support taken substantially upon a plane passing along section line 4—4 of Fig. 2.

I claim:

The ornamental design for an ash tray, as shown.
